UNITED STATES PATENT OFFICE.

FREDRICK S. DICKINSON, OF NEW YORK, N.Y.

METHOD OF CONSTRUCTING PNEUMATIC TIRES.

1,294,063.

Specification of Letters Patent. Patented Feb. 11, 1919.

Original application filed February 26, 1915, Serial No. 10,667. Divided and this application filed August 1, 1918. Serial No. 247,713.

To all whom it may concern:

Be it known that I, FREDRICK S. DICKINSON, a citizen of the United States, and resident of New York, in the county and State of New York, have invented certain new and useful Improvements in Methods of Constructing Pneumatic Tires, of which the following is a specification, the subject-matter of this application being a division 5 from my previous pending application, Serial No. 10,667, filed February 26, 1915.

This invention relates to methods of constructing pneumatic tires such as are now commonly used upon automobiles and other 15 vehicles and which comprise an elastic shoe or casing which constitutes the outer portion and tread of the tire and incloses the inner air tube and which has an internal textile body fabric or carcass.

20 My improvements have particular relation to that class of such tire shoes or casings in which the internal body fabric is of the "cord" type and made up of cords or threads laid to cover the circumferential area of the shoe or casing, in contradistinction to woven fabrics.

In the usual method of constructing such cord or thread body fabrics for the shoes or casings of pneumatic tires, as now generally employed, the cords or threads are bunched, piled, crowded, packed and distorted at the portion of the body fabric which extends at the sides and rim edges of the shoe or casing, which conditions arise 30 from the necessity of equalizing or compensating for the progressive variable difference in the circumference of the shoe or casing at all points of its area between the edge at the rim bead and the tread or periphery. 35 The packing and distortion of the cords or threads, as just mentioned, to equalize or compensate for the differential circumference, not only fractures and weakens the fibers of which the cords or threads are composed but precludes that uniformity of tension which is requisite to durability in the life or service conditions of the tire.

Heretofore, in some methods of constructing the so-called "cord" tires of the class to 40 which my improvements relate, the differential circumference has been equalized or compensated for by flattening the cords or threads and laying up the narrow edges of the cords, which are thus produced, against 45 or at right angles to the core or mandrel on

which the cord fabric is formed, at that portion thereof which corresponds to the side edge or rim bead of the tire, from which point the flattened cords are gradually twisted until the wide or flat side thereof 50 lays against or parallel to that portion of the core or mandrel which corresponds to the periphery or tread portion of the tire. While this method of construction compensates for the variable circumference, in that 55 it serves to extend over or cover the full variable circumferential area of the tire shoe or casing, the flattening of the cords or threads fractures the fibers thereof and thereby materially weakens the fabric, and 60 the twisting not only precludes the maintenance of uniformity of tension throughout the length of the cords or threads but it creates frictional action between the cords by displacing the position of the twist when 65 the tire is depressed or flexed in service.

The object of my improved method of constructing the casings of pneumatic tires is to effectively overcome the conditions and objectionable features above set forth and 70 produce an improved tire of the "cord" type in which the body fabric will retain all the initial strength of the fibers from which the cords or threads are made up and will insure the requisite uniformity of tension. 75

In the drawings—

Figure 1 is a perspective view, partly in section, of a single-ply construction of the cord body fabric according to my improved method.

Fig. 2 is a cross-section of the core or mandrel over which the cords or threads are laid in constructing the fabric according to my improved method, and illustrating the positional relationship of the cords thereto.

Fig. 3 is a detail cross-section illustrating the single-ply fabric produced by my improved method, in its contour as it would be in a finished tire under inflation.

Fig. 4 is a plan view illustrating the positional relationship of the cords or threads as laid over the core or mandrel on which the fabric is formed.

Fig. 5 is a perspective view, partly in section, illustrating a completed tire shoe or casing constructed according to my improved method and showing a construction thereof in which superimposed plies of the cord body fabric are employed.

Fig. 6 is a plan view corresponding to 110

Fig. 4 and illustrating a modified construction according to my improved method, in which a tape made up of a group of cords or threads is employed and laid in lieu of a single cord.

Fig. 7 is a detail cross-section on the line $\omega-\omega$, Fig. 6.

Corresponding parts in all the figures are denoted by the same reference characters.

10 Referring to the drawings, 1 designates the tire shoe or casing, which comprises the internal fabric body, 2, and the elastic external portion constituting the tread, 3, which casing incloses the usual air tube and 15 is held in connection with the wheel rim in the usual manner.

The improved cord body fabric, as constructed according to my improved method, 20 is constituted by the cords or threads, 4, which are laid to extend over or cover the entire circumferential area of the shoe or casing, the construction being preferably produced by the laying of a continuous length of cord or thread. Any suitable 25 fiber material may be employed for the cords or threads, but they are preferably composed of non-extensible yarns, for instance, combed sea-island cotton spun and twisted in non-extensible yarns of suitable 30 or adapted diameter.

In the method of constructing the body fabric 2, as comprised in my present invention, the cords or threads 4 are turned or looped, as at 5, at the terminal side edges 35 or rim-bead portion of the tire, and at said loops they are laid directly over each other, as at 6, from which point they are spread or diverged or radiated, in a gradual and continuous positional relationship, as at 7, at 40 the circumferential side portions of the tire, so that they relatively spread and the under cord gradually emerges from beneath the upper cord, until they extend over or cover the full area of the greatest circumference 45 of the tire at the tread or peripheral portion thereof, as at 8. The cord body fabric, under the improved method of construction above described, thus extends over or covers the full area of the varying or differential 50 circumference of the tire shoe or casing, without packing or distortion or flattening or twisting of the cords or threads, and equalizes or compensates for the differential circumference at all points thereof. It will 55 be noted that the laying up of the cords or threads is preferably such that they extend on a line diagonal or at an oblique angle to the transverse or segmental cross-sectional plane of the tire (see Fig. 4). In 60 a cord body fabric employing single cords or threads, as constructed according to my improved method, the gradually diverging or radiating cords have a position closely side by side at that portion of the fabric which 65 is at the point of greatest circumference of

the tire, which is where the cords cross the tread portion of periphery, as shown in Fig. 4.

In carrying out the improved method of 70 constructing the cord body fabric, according to my invention, the cords are preferably laid over a suitable core or mandrel, 10, of such size and form as to conform to the inner contour of the finished tire shoe or casing, which core is suitably mounted 75 rotatably to be advanced in step movements graduated according to the diameter of the cord or thread used. At opposite sides of said mandrel, in one type of bead-edge anchorage construction as adapted to my 80 present improvements, are mounted rings or hoops, 11, which are initially held in position a suitable distance away from the core, as shown in Fig. 2, the relative position of said rings and core being such that the cords 85 or threads when laid will have a proper length to extend over the periphery of the core and downwardly at each side thereof a sufficient distance to permit the rings 11 and the looped portions 5 of the cords to 90 form the side edges or bead of the tire shoe or casing. The cords or threads are then laid in a continuous length passing under and around one of the side rings 11 or anchorage members employed, and from 95 thence over and across the periphery of the core 10 and under and around the other side ring 11 or anchorage member, in the positional structural relationship of the completed cord fabric as hereinbefore described, 100 the loops 5 being formed around the rings 11 or anchorage members and the gradual divergence or radiation of the cords being from this point over and across the periphery of the core, as at 7-8 (Fig. 4). The 105 laying of the cords in the manner just indicated is continued until the fabric corresponding to the entire circumference of the tire shoe or casing is completed, after which the rings 11 or anchorage members are 110 brought inwardly and set against the sides of the core and suitably clamped in this position in which the finished fabric will conform to the circumferential annular and segmental cross-sectional contour of the finished shoe or casing. If a plurality of plies are to be employed in the body fabric, as shown in Fig. 5, the succeeding plies are laid up in like manner as that just described, but preferably at an oblique angle or diagonal 115 position opposite to that of the preceding ply.

When the desired number of plies have been laid up in the foregoing manner, an elastic bond is created between all the cords 120 or threads by the application of a caoutchouc filler, this being preferably accomplished by impregnating the entire body fabric with soluble rubber in a vacuum chamber. There 125 is thus produced a homogeneous caoutchouc 130

and fabric carcass conforming to the contour of the finished shoe or casing and comprising a casing of rubber in which are embedded reinforcing cords or threads. After 5 completion of the homogeneous cord fabric and caoutchouc carcass or casing, as just described, the latter is placed in association with the elastic external portion of the shoe or casing, which incloses the body fabric or 10 carcass and forms the usual cushion and tread 3 of the tire, and the complete shoe or casing thus produced is vulcanized or cured in the customary manner.

In carrying out the improved method of 15 constructing the cord body fabric, as comprised in my present invention and improvements, I do not restrict myself to any particular mechanism or devices for laying up or forming the improved body fabric which 20 is produced by my method, as this may be accomplished in various ways. For instance, the cords or threads may be initially wound or looped over the two rings 11 or anchorage members employed, with the latter 25 positioned a proper distance apart to allow sufficient length of cord extending between them to form the width of body fabric which is to pass at the determined oblique angle from the edge or bead of one side of 30 the tire to the edge or bead of the other side; then, into the annular completed ring or hoop of the cord fabric so formed upon the side rings 11 or anchorage members, a sectional core or mandrel is inserted, with the 35 periphery thereof midway between the two side rings 11 or anchorage members, after which said side rings are relatively turned in opposite directions to lay the cords over the core at the proper oblique angle in the 40 relative position as hereinbefore described and as shown in Fig. 4, in which the cords overlay each other at the side bends or loops 5 and gradually diverge or radiate therefrom so that the under cord emerges from 45 beneath the upper cord, as at 7, until the cords lay parallel and side by side, as at 8, over the area of the peripheral portion of the core.

My improvements as herein described are 50 not restricted to any particular type of anchorage means or devices, nor to any particular method of producing the diagonal or oblique lay of the cords, as the latter may be accomplished in any preferred manner or 55 method of laying. For instance, the cords may be initially laid directly across from and between the bead-edge supports or anchorage means in a plane substantially transverse to that of the annulus of the tire, and 60 then the laid cords may be shifted at one or both bead-edge portions to change the angle and produce the diagonal or oblique lay, or one or both of the bead-edge supports may be shifted to produce the same effect in the 65 diagonal or oblique lay, or the cords may be

initially laid in said diagonal or oblique position. The shifting method, either of the cords or bead-edge supports, as just referred to, forms no part of my present application but is embodied in my original application Serial No. 10,667, filed February 26, 1915, from which this case is divided.

The rings 11, upon which the cords or threads are looped or wound, when employed as the anchorage means in carrying 75 out my improved method of construction, may be of any suitable material, such as a metallic wire or a textile cord, and they preferably remain within the completed fabric, so that they form beads or retaining 80 rings within the selvage edge of the fabric at the loops (Fig. 5), at the side edges or beads of the shoe or casing, by which the tire is held in position on the wheel rim.

Under some circumstances of tire construction, according to my improved method, a single ply of cord body fabric, as shown in Figs. 1 and 4, may be employed, but under some circumstances a plurality of layers or plies or laminations of the fabric may be 90 employed, as shown in Fig. 5, and where a plurality of plies are employed the respective plies are preferably laid to extend in opposite directions in their diagonal or oblique lines with relation to the segmental 95 cross-section of the shoe or casing, which reverse positions of the plies are best adapted to equalize all stresses or strains when the tire is depressed or flexed in service.

Under some circumstances of construction, according to my improved method, in lieu of laying a single cord or thread (as illustrated in Fig. 4), the cord body fabric may be laid from a tape made up of groups or multiples of single cords or threads, as in 100 the modification illustrated in Figs. 6 and 7. The tape shown at 12, in this method of construction, is laid in the same manner as the single cord or thread construction, with the side loops, 5, extending around the rings or 105 hoops 11 or anchorage members, at which point the tapes directly overlie each other and from which point the tapes gradually diverge or radiate, as at 7, so that the under tape gradually emerges from beneath the upper tape and the tapes overlie and extend over or cover, as at 8, the increased circumferential area of the peripheral or tread portion of the shoe or casing. In view of the increased width of the tape unit, in contradistinction to the single cord construction as shown in Fig. 4, it is not necessary that the tapes lay side by side at the peripheral or tread portion, as is the case with the single cord method of construction, but the 110 tapes are laid to overlap a suitable portion of their respective widths, as shown at 14, at the peripheral or tread portion, which overlapping construction fully equalizes and 115 compensates for the differential diameters in 120 125 130

the same manner as the single cord construction and at the same time produces a double thickness of the cord body fabric at all points throughout its area (see Fig. 7), this method of construction being especially adapted to produce a single ply fabric in that the tape method of construction affords substantially the same thickness and strength of a double ply fabric formed by 10 the single cord method of construction.

I do not desire to be understood as limiting myself to the detail features of the method of construction as herein illustrated and described, as it is manifest that variations therein may be resorted to in the adaptation of the method of construction to varying conditions according to the type of pneumatic tire casing to which the cord body fabric as produced by my method is to be 15 applied, without departing from the spirit and scope of my invention and improvements. I therefore reserve the right to all such variations and modifications as properly fall within the scope of my invention 20 and the terms of the following claims.

Having thus described my invention, I claim and desire to secure by Letters Patent:

1. The method of constructing the internal body fabric for the shoe or casing of 30 pneumatic tires of the "cord" type, which consists in laying a length of textile cord or thread with turns or loops at an angle to the annulus of the tire at the terminal side edges or rim-bead portion thereof and with 35 the cord laid over itself at said turns or loops and spread or diverged from said looped portion in a gradual and continuous relationship at the circumferential side portions of the tire so that the under portion 40 of the length of cord gradually emerges from beneath the upper portion thereof and said under and upper portions relatively spread and extend over the enlarged circumferential area and conjointly cover the space area of the greatest circumference of the tire at the tread or peripheral portion thereof, to equalize or compensate for the progressive variable circumference of the tire and 45 entirely cover the same by said length of cord itself without distortion or flattening or twisting of the textile cord.

2. The method of constructing the internal body fabric for the shoe or casing of 55 pneumatic tires of the "cord" type, which consists in laying the cords or threads of which the body fabric is composed in overlying position at an angle to the annulus of the tire at the terminal side edges or rim-bead portion thereof and with the cords 60 relatively spread or diverged from said overlying position at the side-edge portion of the tire in a gradual and continuous positional relationship at the circumferential side portions of the tire so that the under 65

length of cord gradually emerges from beneath the upper length and said under and upper lengths relatively spread and extend over the enlarged circumferential area and conjointly cover the space area of the greatest circumference of the tire at the tread or peripheral portion thereof, to equalize or compensate for the progressive variable circumference of the tire and entirely cover the same by the spread of said length of 70 cords from their side-edge position at an angle to the annulus of the tire without distortion or flattening or twisting of the cords.

3. The method of constructing the internal body fabric for the shoe or casing of pneumatic tires of the "cord" type, which consists in laying the cords or threads of which the body fabric is composed in a single thickness or ply with portions relatively spread or diverged and emerging one from beneath the other at the circumferential side portions of the tire to the tread or peripheral portion thereof in a gradual and continuous positional relationship so 85 that said portions relatively spread and extend over the enlarged circumferential area and conjointly cover the space area of the progressive variable circumference of the tire at the tread or peripheral portion thereof, to equalize or compensate for the progressive variable circumference of the tire and entirely cover the same by the spreading and divergent cords of said single thickness or ply without distortion or flattening 90 or twisting of the cords.

4. The method of constructing the internal body fabric for the shoe or casing of pneumatic tires of the "cord" type, which consists in laying the cords or threads of 105 which the body fabric is composed in overlying position at an angle to the annulus of the tire at the terminal side edges or rim-bead portion thereof and with the cords relatively spread or diverged from said overlying position at the side-edge portion of the tire in a gradual and continuous positional relationship at the circumferential side portions of the tire and extending side by side in abutting position at the peripheral 110 or tread portion thereof so that the under length of cord gradually emerges from beneath the upper length and said under and upper lengths relatively spread and extend over the enlarged circumferential area and 115 conjointly cover the space area of the greatest circumference of the tire at the tread or peripheral portion thereof, to equalize or compensate for the progressive variable circumference of the tire and entirely cover the same by said spreading and abutting cords without distortion or flattening or twisting 120 of the cords.

5. The method of constructing the internal body fabric for the shoe or casing of 130

- pneumatic tires of the "cord" type, which consists in laying a plurality of layers or plies respectively comprising cords or threads laid in overlying position at an angle to the annulus of the tire at the terminal side edges or rim-bead portion thereof and with the cords relatively spread or diverged from said overlying position at the side-edge portion of the tire in a gradual and continuous positional relationship at the circumferential side portions of the tire so that in each respective layer the divergent portions of the lengths of cord relatively spread and extend over the enlarged circumferential area to conjointly and entirely cover the space area of the progressive variable circumference of the tire without distortion or flattening or twisting of the cords.
6. The method of constructing the internal body fabric for the shoe or casing of pneumatic tires of the "cord" type, which consists in anchoring the cords or threads of which the body fabric is composed at the terminal side edges of the tire and laying the cords in engagement with the anchoring means in overlying position at an angle to the annulus of the tire and with the cords spread or diverged from said overlying position in a gradual positional relationship at the circumferential side portions of the tire so that the under length of cord gradually emerges from beneath the upper length and said under and upper lengths relatively spread and extend over the enlarged circumferential area and conjointly cover the space area of the greatest circumference of the tire at the tread or peripheral portion thereof, to equalize or compensate for the progressive variable circumference of the tire and entirely cover the same by the spread of said length of cords from their side-edge position at an angle to the annulus of the tire without distortion or flattening or twisting of the cords.
7. The method of constructing the internal body fabric for the shoe or casing of pneumatic tires of the "cord" type, which consists in anchoring the cords or threads of which the body fabric is composed at the terminal side edges of the tire and laying the cords with loops or turns engaging said anchoring means at an angle to the annulus of the tire and with the cords extending over each other at said looped portions and spread or diverged therefrom in a gradual and continuous positional relationship at the circumferential side portions of the tire so that the under cords gradually emerge from beneath the upper cords and the under and upper lengths from said loops relatively spread and extend over the enlarged circumferential area and conjointly cover the space area of the greatest circumference of the tire at the tread or peripheral portion thereof, to equalize or compensate for the progressive variable circumference of the tire and entirely cover the same by the spread of said length of cords from their loop at an angle to the annulus of the tire without distortion or flattening or twisting of the cords.
8. The method of making a hollow annular cord web, which comprises laying cord onto supports of different diameters to form two series of cord elements, the cord being so arranged that the cord elements of one series lie between the cord elements of the other series at the periphery of the annular cord web but not at the sides of said web.
9. The method of constructing the internal body fabric for the shoe or casing of pneumatic tires of the "cord" type, which consists in laying cord onto a mandrel or former of one diameter and on bead-edge anchorages of lesser diameter, to form two series of cord elements and in such position that the cord elements of one series overlie the cord elements of the other series at an angle to the annulus of the tire at the rim-bead portion, and spreading or diverging said cord elements from said overlying position in a gradual positional relationship in which the under cord elements of one series emerge from beneath the outer cord elements of the other series at the circumferential side portions of the tire and the space area at the tread or peripheral portion of the tire is covered conjointly by the cord elements of both series, to equalize or compensate for and cover the progressive variable circumference of the tire.
- In testimony whereof I have signed the foregoing specification.
- FREDRICK S. DICKINSON.
